DESIGN FOR A CURTAIN

Jay C. Lafferty, Jr., Philadelphia, Pa., assignor to North American Lace Company, Inc., Philadelphia, Pa.

Application August 24, 1934, Serial No. 53,042

Term of patent 3½ years

To all whom it may concern:

Be it known that I, JAY C. LAFFERTY, JR., a citizen of the United States residing at Philadelphia in the county of Philadelphia and State of Pennsylvania, have invented a new, original, and ornamental Design for a Curtain of which the following is a specification, reference being had to the accompanying drawing, forming part thereof, in which the figure is an inverted plan view of a curtain showing my new design.

I claim:

The ornamental design for a curtain substantially as shown.

In testimony whereof I affix my signature.

JAY C. LAFFERTY, JR.
